UNITED STATES PATENT OFFICE

BEATRICE SPIERS, OF PHILADELPHIA, PENNSYLVANIA

COMBINATION GARMENT.

Application filed May 28, 1930, Serial No. 456,729. Renewed May 29, 1931.

The present invention relates to new and useful improvements in wearing apparel and more particularly to a one-piece garment constituting an outer garment and drawers 5 and has for a primary object to provide, in a manner as hereinafter set forth, a garment of this character which may be expeditiously put on or taken off in the manner of a coat-shirt.

10 Other objects of the invention are to provide a combination garment of the character described which will be comparatively simple in construction, strong, durable, efficient in its use and which may be manufactured 15 at low cost.

All of the foregoing and still further objects and advantages of the invention may become apparent from a study of the following specification, taken in connection with 20 the accompanying drawings, wherein like characters designate corresponding parts throughout the several views, and wherein:

Figure 1 is a view in front elevation of a combination garment constructed in accordance with this invention in closed position,

Figure 2 is a front view of the garment showing the crotch portions unbuttoned and separated,

Figure 3 is a view in front elevation of the 25 garment with the sides unbuttoned and thrown back in a manner to expose the interior construction and show the arrangement of the crotch members.

Figure 4 is a fragmentary detail view on 30 an enlarged scale in rear elevation of a lower portion of the garment.

Figure 5 is a fragmentary detail view on 35 an enlarged scale and in rear elevation showing a portion of one of the legs.

Referring to the drawings in detail, it will 40 be seen that the reference numeral 1 designates the body portion of the garment which is adapted to be buttoned together as at 2 throughout its length. 3 and 4 designate 45 depending leg portions. As best seen in Figure 4 of the drawings, a lower rear portion of the garment is slit as at 5 in a manner to provide an extension 6 on the leg portion 3. A flap 7 is stitched to one of the edges of the 50 garment which defines one side of the slit

5 and has formed therein a button hole 8 for the reception of a button 9 on the leg portion 3 at the rear thereof in a manner to secure said flap 7 in closed position to close the slit 5.

Buttons 10 are provided on the free end portion of the extension 6. Still referring to Figure 4 of the drawings, it will be seen that the inner rear portion of the leg 4 has stitched thereon, a gore 11 to which is stitched another gore 12. The lower end portion of the flap 7 is stitched to the adjacent side of the second named gore 12 and a binding 14 is provided which extends over the free end of the flap 7, the gore 12 and the adjacent 65 marginal portion of the gore 11. Buttons 15 are provided on the binding 14.

The free edges of the leg portions of the garment are cut at an obtuse angle as designated by the reference numeral 16 (see Figure 3) and provided with button holes 17. Above the obtuse edges 16 and adjacent thereto the garment has formed therein the button holes 18 and when the garment is put on the flap 7 is brought forwardly between the 75 limbs of the wearer and the button 19 is inserted through each of the button holes 18. The buttons 15 are inserted through the button holes 17 on the obtuse marginal portion 16 of the leg portion 4. The extension 6 is 80 brought forwardly between the limbs of the wearer and the buttons 10 thereon are inserted in the button-holes 17 of the obtuse marginal portion 16 of the leg portions 3.

The gores 11 and 12 and the flap 7, as well 85 as the leg portions 3 and 4 are of a configuration to give sufficient fullness to the seat portion of the garment to permit bending over of the body of the wearer and provide a maximum of comfort. It is understood, of course, that bindings or facings are to be provided wherever desired on the marginal portion and edges of the garment. In Figure 3 of the drawings, the reference numeral 20 designates an anchoring seat on the inner side of the extension 6 for anchoring the button 9 thereto.

It is believed that the many advantages of a combination garment constructed in accordance with this invention will be readily 90

understood and although the preferred embodiment of the invention is as illustrated and described, it is to be understood that changes in the details of construction may be had which will fall within the scope of the invention as claimed.

Having thus described my invention, what I claim as new is:

1. A garment comprising a shirt and drawers open in front throughout its length and having an arcuate slit in its rear extending from the lower end thereof to an intermediate portion, said slit providing a pair of leg sections for disposition around the leg of a wearer, the rear portion of one of the leg sections having an integral extension, a flap secured to the marginal rear portion of one of the leg sections for disposition across the slit and detachably connected to the rear portion of the other leg section, said flap extending forwardly and upwardly between the legs of a wearer and detachably connected to the front portions of the garment in a manner to constitute the crotch therefor, the extension disposed between the legs of the wearer and connected to the front portion of its respective leg section.

2. A garment comprising a shirt and drawers open in front throughout its length, said open front adapted to be detachably secured together in overlapping relation, said garment being further provided with an arcuate slit in its rear extending from its lower end to an intermediate portion thereof and providing leg sections for disposition around the leg of a wearer, an integral extension on one of the leg sections, gores secured to the rear portion of the other leg section adjacent the slit, a flap secured to said other leg section at the rear thereof, and extending therefrom across the slit for detachable connection in overlapping relation on the first named leg section, said flap disposed longitudinally with one of the gores and stitched thereto, said flap extending forwardly and upwardly between the legs of a wearer in a manner to provide a crotch and detachably connected to the overlapping front portions of the garment adjacent the lower end thereof, the extension passing between the legs of the wearer and detachably connected to the front portion of its respective leg section.

In testimony whereof I affix my signature.
BEATRICE SPIERS.
